RECOIL ABSORBER

Roy S. Sanford and Alexander Kurti, Woodbury, Conn., assignors to The Autoyre Company, Incorporated, Oakville, Conn., a corporation of Connecticut

Application January 11, 1945, Serial No. 572,266

7 Claims. (Cl. 89—44)

1

This invention relates to recoil devices, more particularly to a device for absorbing the recoil of armament, for example, a machine gun, and the invention has for an object the provision of an improved, lightweight and inexpensive device of this type.

For absorbing the recoil of guns generally of the type not adapted to shoulder firing, some mechanism, either hydraulic or including coil springs, is interposed between the firing portion of the gun and its carriage. Either type of mechanism incorporates a great many working parts and is therefore complicated and difficult to assemble, manufacture and maintain. Furthermore, when in use in the field the problem is complicated by the presence of dirt and mud which clogs the working parts. In one type of machine gun presently in use the recoil unit includes coiled springs and contains fifty-four working parts, all of which may give difficulty because of failure of adjustment and improper operation due to the presence of dirt and mud. Likewise, the problem of supply of repair parts becomes difficult as all of the parts must be available in field stock. The cost of such a unit is necessarily high and may constitute a substantial part of the cost of the entire gun. Accordingly it is a further object of this invention to provide a recoil device for a machine gun, for example, which may be made of one piece or of only a few pieces, which is superior in operation, eliminates many problems of maintenance and improper functioning due to dirt and mud, is inexpensive to construct, and with respect to which repair and replacement are virtually eliminated.

A principal object of the invention, therefore, is to provide a recoil device adapted to be interposed between the operating portion of the gun and its carriage and comprising a single sheet of material suitably punched and formed to yield the desired structure.

Another important object of the invention is to provide a recoil device of the type described which includes leaf spring inertia absorbing elements instead of coiled spring elements.

Another object is to provide a device of the kind described which may be formed with a minimum of operations and has its parts so adapted and arranged that different portions thereof may be given different degrees of resiliency.

Still another object is to provide a device of the type described which will absorb the recoil without deflecting the predetermined aiming of the gun sufficiently to interfere with its accuracy respecting the target.

2

Another object is to provide a recoil device having its parts so adapted and arranged that it will withstand abuse in service and not become distorted.

5 Yet another aim is to provide in a recoil device resilient parts to absorb the recoil and hinged parts to carry the weight of the gun independently of the resilient means.

Still another object is to provide a recoil device in which the resilient members are so formed and proportioned as to absorb the recoil frequently in the intended manner, without possibility of fatigue failure of any portion thereof.

10 Another object is to provide a recoil device having the qualities aforesaid but which is light in weight.

Another object is to provide in connection with a recoil device as described a deflecting plate upon which the spent cartridges may be discharged 15 from the gun and deflected to one side in order that they may not accumulate within the recoil mechanism to cause jamming thereof.

Other and further objects will appear as the description proceeds.

20 In carrying out the invention in one form we provide a suitably punched and formed single piece of resilient material properly tempered in those parts thereof intended to exercise the recoil absorbing function. The device includes a body portion, two pairs of linkage arms to support the gun with respect to its carriage, members maintaining the parts of each pair rigidly with respect to each other, and leaf type spring arms interposed between the body and each pair of linkage 25 arms. The body portion and the linkage arms may be reinforced as desired and holes are provided in the body portion and the linkage arms whereby the device may be suitably connected intermediate the body of the gun and its carriage.

30 In the drawings:

Fig. 1 is a side elevation of one type of gun to which the device is adapted;

Fig. 2 is a perspective view of the recoil device proper;

40 Fig. 3 is a cross section taken on the line 3—3 of Fig. 2;

Fig. 4 is a cross section taken on the line 4—4 of Fig. 2;

Fig. 5 is a cross section taken on the line 5—5 of Fig. 2; and

Fig. 6 is a diagram to indicate certain features of the functioning of the device.

Referring first to Fig. 1, there is shown one type of gun, namely, a machine gun to which the 50 device is adapted and including the gun proper 10

and an under-carriage 11. Interposed between the gun 10 and the carriage 11 and connected therebetween by means to be described is the recoil device of our invention, shown generally by the reference numeral 12.

The device (Fig. 2) includes a base portion or principal support which is comprised of a neck 13 forming a rigid connection between the side members 14. The latter are preferably of right angled cross section and include a horizontally disposed leg 15 and a vertically disposed leg 16 which, together with the neck 13, form a rigid, elongated principal support for the remaining parts of the device.

At their extremities the legs 16 may be slightly enlarged into a substantially circular form to provide ears 17 through each of which is an aperture 18. The horizontally measured distance between the centers of the apertures 18 may vary depending upon the size of the gun to which the device is to be attached and the recoil characteristics of the same generally.

Extending in either direction from the neck 13 and unitary therewith is the forward resilient arm 19 and the rearward resilient arm 20. The arm 19 is substantially right angled in form, as most clearly seen in Fig. 1, and the arm 20 is provided with a sinuous curve including quadrant portions 21, 22 and 23 (Fig. 5), while the arm 19 is provided with a similar quadrant-shaped corner 24. At its upper extremity the arm 19 continues transversely in both directions to form the member 25 disposed at a sufficient distance above the neck 13 to yield a free vertical length of spring arm 19 which, together with the horizontally extending length thereof, is intended to provide recoil absorbing characteristics of the desired degree. The transverse member 25 is formed at its extremities into portions 26 which are extended downwardly to form the vertically extending links 27. At its upper end each link 27 is provided with an aperture 28 and at its lower end with an aperture 29, the aperture 29 in each link 27 being in register with its associated aperture 18. To provide additional rigidity the links 27 may be provided on one edge with a flange 31 as shown. The transverse member 25 has in its upper edge a concave aperture 30 for clearing the barrel of the gun.

The rearward resilient arm 20 at its upper end continues transversely in both directions to form a member 32 and then at right angles thereto into portions 33. The latter continue into the downwardly extending links 34, similar in construction and function to the links 27. At its upper end each link is provided with an aperture 35 and at its lower end with an aperture 36 in register with associated apertures 18.

Inasmuch as the recoil device is sometimes located below the opening of the gun through which spent cartridges are discharged, it is preferred to provide an element in connection with the recoil device which will deflect the spent cartridges harmlessly to one side to avoid their interference with proper working of the device. In the present embodiment this element is shown as a wing 41 formed integrally with a side member 14 and extending upwardly and transversely of the device at an angle of approximately 30° as seen in Figs. 3 and 4. Accordingly, cartridges dropping from above and impinging on the wing 41 are deflected harmlessly to one side.

The recoil absorber of our invention may be attached to the gun and its carriage in any suitable manner, but there is shown by way of ex-

ample bolts 42 passing through the apertures 28 and 35, the said bolts engaging suitably formed parts of the gun which constitute no part of the present invention. At its lower side the device 5 is similarly engaged with the carriage by bolts 43 passing through the apertures 18, 29 and 36 and through suitable members connected to the carriage and likewise forming no part of the invention. Bolts 42 and 43 have a free fit in their 10 respective apertures to permit the links 27 and 34 to oscillate thereabout in a manner to be described.

It will be appreciated that the design of our structure is such that it affords great flexibility in manufacture while permitting the desired shape and strength to be imparted to the resilient elements. That is to say, the lateral, vertical and horizontal spacing as well as the size of the apertures 18, 28, 29, 35 and 36 and the other affected dimensions may be readily adapted to guns and carriages already in use and, therefore, may replace existing devices which have proved complicated and unsatisfactory.

It will be observed that in operation the links 25 and 34 will oscillate with respect to their upper and lower points of attachment to permit a parallel movement between the gun proper and its carriage so that the aiming of the gun is disturbed only insignificantly during firing. This 20 advantage is brought out particularly in Fig. 6 in which the neutral or non-firing position of the absorber is indicated by a vertical line. Such line would correspond to the vertical center line of pairs of apertures 35 and 36 or 28 and 29, and by 30 way of illustration the vertical center distance is shown as 4".

Upon the firing of the first cartridge the mechanism of the gun is such that a maximum recoil occurs and, in one type of gun, this may produce 40 a substantially horizontal displacement of the barrel of 1.000" and a substantially vertical displacement of the barrel of 0.150". However, succeeding firings do not produce such maximum recoil but only a substantially horizontal displacement on one side of neutral of 0.500" corresponding to a substantially vertical displacement of the barrel of 0.040". The horizontally measured counter-recoil on the initial, as well as succeeding firings is shown as 0.500" with a substantially vertical displacement again of -0.040". Otherwise expressed, by providing a vertical center distance between the apertures 28 and 29, and 35 and 36, of the maximum amount permitted by the required position of the gun above the carriage, we attain a minimum vertical offset, in this instance approximately $\frac{1}{25}$ ", and this has been found not to affect the accuracy of the gun. It 50 will be understood that guns of the type to which the invention is applicable are not generally fired by sighting on the target but only by an approximate initial sighting. Correction and maintenance of the sighting is by the use of tracer bullets.

As the links 27 and 34 rock about their lower connections 43, the transverse members 25 and 32 will be oscillated and moved upwardly and downwardly thereby producing deflection in the spring elements 19 and 20 to absorb the recoil. The arcuate portions 20, 21, 22 and 23 serve to 70 transmit the stresses of deflection from the vertical arms of the elements 19 and 20 to the horizontal portions thereof in a manner calculated to yield the least strain at the corners and thus reduce the possibility of fatigue failure to a negligible degree. Inasmuch as the greater

mass of the gun is at the rear it is required that the major portion of the recoil be absorbed on the rearward spring element 20, and the additional arcuate portions 21 and 22 are provided in that element in order to yield additional zones of easier deflection at 50 and 51.

It will be understood that by suitable processes the resilient members 19 and 20 may be heat-treated to yield the required spring temper, and the remaining portions of the device heat-treated differently to impart the requisite tensile strength without rendering them brittle. Furthermore, it will be apprehended that the device need not be made of a single sheet of metal but may comprise several parts welded, riveted or otherwise fastened. In this event all parts other than the spring elements 19 and 20 may be made of a cheaper material having the required structural characteristics and the spring elements may be made of the more expensive spring steel.

It is to be particularly noted that the means of attaching the recoil device to the gun forms no part of the invention since different types of armament may require different types of connections. For simplicity we have shown apertures adapted to be engaged by pins. Other modes of connection will suggest themselves without departing in any way from the essence of the invention.

Neither is it intended that the invention be limited to a device entirely of sheet metal as parts other than the resilient elements 19 and 20 may be made of forgings or castings reinforced in any suitable manner.

The links 27 and 34 are shown as spaced slightly farther apart at the upper portion than at the lower portion. This is no feature of the invention but is done merely to indicate that the spacing of the upper ends of the links may be wider or narrower than the opposite ends to adapt the device to different dimensions of parts to which it is connected. Nor is it necessary that the transverse spacing of the two ends of the body portion be equal since one may be wider or narrower than the other depending upon the dimensions of the carriage and the mode of attachment thereto. It will also be understood that the spring elements 19 and 20 may be of different dimensions and of different tempers to produce selected results in the action of the recoil device.

While we have shown particular embodiments of our invention, it will be understood, of course, that we do not wish to be limited thereto since many modifications may be made, and we, therefore, contemplate by the appended claims to cover any such modifications as fall within the true spirit and scope of our invention.

Having thus described our invention, what we claim and desire to secure by Letters Patent is:

1. A device for absorbing recoil adapted to be interposed between a recoiling body and its fixed support comprising a one-piece member including a base portion, oppositely extending resilient arms forming continuations of said base portion and disposed substantially at right angles to said base portion, each said arm terminating in a T-shaped head, the ends of the head of the T continuing substantially parallel to the said arms and substantially coextensive therewith to form link elements terminating adjacent said base portion, each element having an aperture formed therein adjacent each end thereof, the said apertures being adapted to receive means to attach the device to the body and to the support.

2. A device for absorbing recoil adapted to be

interposed between a recoiling body and its fixed support comprising a one-piece member including a base portion, a longitudinally extending upwardly directed flange extending from either side of said base portion and having an aperture through each end thereof, a resilient arm extending from each end of said base portion and directed substantially at right angles to said base portion, each said arm terminating at its upper extremity in a transverse T-shaped head, each end of said head having an aperture formed therein, the axis of each said last mentioned aperture being parallel to and substantially in vertical alignment with the axis of each adjacent first mentioned aperture, all said apertures being adapted to receive means for attaching the device to the body and the support.

3. A device for absorbing recoil adapted to be interposed between a recoiling body and its fixed support comprising a base portion including oppositely positioned upwardly extending flanges along the two longitudinal edges thereof and a neck connecting said flanges, said flanges having an aperture adjacent each end thereof, resilient arms extending outwardly from each side of said neck and substantially parallel to said flanges for a portion thereof and continuing upwardly substantially at right angles to said flanges, each said arm terminating at its upper end in a substantially T-shaped head including ears substantially in alignment with said flanges, each said ear having an aperture formed therein, the said aperture in each said ear having its axis parallel to the nearest adjacent aperture in a flange, said apertures being adapted to receive means for attaching the device to the body and the support.

4. A device for absorbing recoil adapted to be interposed between a recoiling body and its fixed support comprising a base portion including oppositely positioned upwardly extending flanges along the two longitudinal edges thereof and a neck connecting said flanges, a resilient arm extending outwardly and upwardly from each side of said neck, each said arm terminating at its upper end in a T-shaped head, a downwardly extending link at the extremity of each end of said head and overlapping said flanges adjacent the ends thereof, each said link having apertures through the upper and lower ends thereof, respectively, and each said flange having an aperture formed therein and through each end thereof, each said last mentioned aperture being in register with the associated aperture in said link, and all said apertures being adapted to receive means for engaging the device with the body and the support.

5. A device for absorbing recoil adapted to be interposed between a recoiling body and its fixed support comprising an elongated base portion including upturned flanges along two opposed edges of said base portion and substantially coextensive with the major axis of said base portion and a neck positioned substantially at the minor axis of said base portion, oppositely extending resilient arms attached to said neck and substantially parallel to said edges and deformed upwardly at a point substantially in alignment with the associated ends of said flanges, each arm being provided at its upper extremity with a transverse member deformed at its ends to form links substantially in alignment with the planes of said flanges and continuing downwardly to overlap said flanges, the said links being freely movable with respect to said flanges upon distortion of said resilient

arms, each said link having an aperture formed therein and adjacent the upper end thereof, and another aperture formed therein adjacent the lower end thereof, each said flange having an aperture formed in each end thereof, the lower apertures of said links being in register with the associated apertures in said flanges, all said apertures being adapted to receive means for engaging the device with the body and the support.

6. A device for absorbing recoil adapted to be interposed between a recoiling body and its fixed support comprising a base portion, a plurality of rigid legs forming part of said base portion, each said leg including means substantially in a common plane for attaching the device to the support, a plurality of resilient arms extending from said base portion and having means at the free end thereof for attaching the device to the body and linkage means intermediate both said attaching means whereby recoil movement of the device is confined to a path substantially parallel to the said plane.

7. A device for absorbing recoil adapted to be interposed between a recoiling body and its fixed support comprising a base portion, a plurality of rigid arms forming part of said base portion, each said arm having an aperture at the free end thereof for attaching the device to the support, a pair of resilient members extending oppositely from and attached to said base, said members being deflectable in the direction of recoil and the plane of deflection of said members being parallel to the plane of recoil, an in-
